WELL PACKER

John M. Hamilton, Odessa, Tex.

Application May 18, 1940, Serial No. 336,028

6 Claims. (Cl. 166—10)

My invention relates to improvements in well packers and has as one of the principal objects thereof the provision of a well packer or device so constructed and arranged whereby the same 5 may be readily actuated to pack or seal a well under practical conditions.

Another object of my invention is to provide a packer of the above described character which is capable of being readily expanded into engagement with the well wall or the like in a manner to isolate the oil bearing stratum from water either above or below the stratum and thus permit, if desired, the casing or tube to be perforated opposite the stratum to admit inflow of the oil.

15 A further object of my invention is to provide a packer of the above described character equipped with means whereby said packer may be expanded and maintained in expanded position.

20 A special object of my invention is to provide a packer so constructed and arranged whereby the well may be chemically treated while packed.

An important object of my invention is to provide a packer of the character described which is 25 simple in construction, durable in use, efficient in operation and economical in manufacture.

Other objects and advantages will be apparent from the following description, appended claims and annexed drawings.

30 Referring to the drawings wherein like reference characters designate like parts throughout the several views:

Figure 1 is a side elevation of my invention, partly in section, illustrating the same positioned within a well.

35 Figure 2 is a view similar to Figure 1 but illustrating the packer-sleeve in expanded position.

Figure 3 is an enlarged disassembled vertical sectional view of my invention.

40 Figure 4 is a top plan view taken on the line 4—4 of Figure 3.

Figure 5 is a sectional view taken on the line 5—5 of Figure 3.

In practicing my invention, in the embodiment 45 illustrated in the drawings, I provide a casing or tube 5 having upper, lower and interjacent sections 6, 7 and 8 respectively, with the latter connecting the former together. The interjacent section 8 is fashioned with upper and lower portions 9 and 10 respectively and which are threadedly connected together as at 11, said upper portion being formed convexly protuberant and of a rotund ellipsomic contour. The lower portion 10 is disposed within an elongated cotyloid shell 12 having its base or bottom 13 threadedly con-

nected to the upper and lower ends of the lower and interjacent sections respectively as at 14.

The inner face of the side 15 of the shell is circumspatially arranged with respect to the lower portion 10 and coacts with the periphery of the portion 10 to define a plunger chamber 16. The plunger chamber 16 has disposed therein (as illustrated in Figure 1) an elongated expandable packer-sleeve or plunger 17 slidably mounted about the portion 10. The sleeve 17 is of a normal diameter slightly in excess of the inside diameter of the shell to maintain the sleeve slightly compressed therein to form a sliding seal with said shell.

The shell, superjacent its base, is formed with a recurvate portion 18 to define a seat 19 for the lower end of the sleeve 17 to maintain the latter in spatiality with the base. The lower end of the portion 10, between the base and the sleeve, is provided with a plurality of ports 20 through which fluid is forced into the shell to actuate the plunger 20 or sleeve upwardly within the shell and in expanded condition over the portion 9. Due to the rotundity of the portion 9, it serves to dispose the plunger in compressed and sealed relation against the well wall W to effect packing of the well as 25 clearly illustrated in Figure 2 of the drawings.

In order to limit the upward movement of the plunger, the lower end of the upper section 6 of the tube has fixed thereto a collar 21 for engagement with the upward end of the plunger.

30 The upper end of the shell is provided with a plurality of outlet openings or ports 22 through which the fluid escapes, thus, when said ports 22 are opened by the upward movement of the plunger further actuation of the plunger is precluded. The bore of the plunger 17 is formed with an interjacent concave portion 23 to effect firm seating with the section 8 when actuated thereover. The plunger may be actuated into the shell from the portion 9 by means of a suitable tool (not shown) inserted into the well and engaging and applying pressure to the upper end of the plunger.

In order to chemically treat the well wall, for instance by applying acid to a porous section adjacent a lime section to increase the porosity of the lime section, acid is forced into the shell and outwardly through the ports 22, the latter being positioned in proximity to the section to be treated. It is to be understood that the acid is introduced into the top of the tube with the bottom closed in a suitable manner, for instance by a disk constructed of a brittle and fragile material, the latter being of a sufficient strength to resist the pressure of the acid. When a disk of this type is employed, the disk is ruptured or broken to open the

end of the tube, upon completion of the treatment, by means of a suitable weight impacted thereagainst.

Inasmuch as the disk construction forms no part of the present invention per se, a more detailed disclosure of the same is not believed necessary.

From the foregoing it will be apparent that I have provided a simple and efficient form of 10 packer which readily lends itself to various uses in conjunction with the operation and drilling of wells.

The terms "upper," "lower" and "bottom" are employed in a relative sense for purposes of 15 description and without intent of limiting the invention thereby as it will be apparent that the structure may be inverted or otherwise disposed whereby such terms might not so clearly apply as when the structure is disposed in the manner 20 illustrated in the drawings.

Without further elaboration, the foregoing will so fully explain the invention that others may, by applying current knowledge, readily adapt the same for use under various conditions of service. 25 Moreover, it is not indispensable that all the features of the invention be used conjointly since they may be employed advantageously in various combinations and sub-combinations.

It is obvious that the invention is not confined 30 to the herein described use therefor as it may be utilized for any purpose to which it is adaptable. It is therefore to be understood that the invention is not limited to the specific construction as illustrated and described as the same is only illustrative of the principles of operation, which are 35 capable of extended application in various forms, and that the invention comprehends all construction within the scope of the appended claims.

What I claim is:

- 40 1. A device of the character described comprising a tube having upper, lower and interjacent sections with the latter connecting the former together, a shell carried by said interjacent section and coacting with the latter to define a plunger 45 chamber therearound, an expandable plunger normally disposed in said chamber and slidably operated on said tube out of said chamber, said interjacent section formed with a convexly protuberant portion superjacent said chamber for 50 receiving and expanding said plunger thereon when the latter is actuated out of said chamber and with said portion coacting with said plunger to dispose the latter in sealing engagement with a well wall.
- 55 2. A device of the character described comprising a tube having upper, lower and interjacent sections with the latter connecting the former together, a shell carried by said interjacent section and coacting with the latter to define a plunger chamber therearound, an expandable plunger normally disposed in said chamber and slidably operated on said tube out of said chamber, said interjacent section formed with a convexly 60 protuberant portion superjacent said chamber for receiving and expanding said plunger thereon when the latter is actuated out of said chamber and with said portion coacting with said plunger to dispose the latter in sealing engagement with a well wall, said tube provided with ports 65 communicating with said chamber for introducing fluid within said chamber for actuating said plunger over said portion.
- 70

municating with said chamber for introducing fluid within said chamber for actuating said plunger over said portion.

3. A device of the character described comprising a tube having upper, lower and interjacent sections with the latter connecting the former together, a shell carried by said interjacent section and coacting with the latter to define a plunger chamber therearound, an expandable plunger normally disposed in said chamber and 5 slidably operated on said tube out of said chamber, said interjacent section formed with a convexly protuberant portion superjacent said chamber for receiving and expanding said plunger thereon when the latter is actuated out of said chamber 10 and with said portion coacting with said plunger to dispose the latter in sealing engagement with a well wall, and means carried by said tube adjacent said portion for engaging said plunger when actuated out of said chamber to position 15 and maintain said plunger over said portion.

4. A device of the character described comprising a tube having upper, lower and interjacent sections with the latter connecting the former together, a shell carried by said interjacent section and coacting with the latter to define a plunger chamber therearound, an expandable plunger normally disposed in said chamber and 25 slidably operated on said tube out of said chamber, said interjacent section formed with a convexly protuberant portion superjacent said chamber for receiving and expanding said plunger thereon when the latter is actuated out of said chamber 30 and with said portion coacting with said plunger to dispose the latter in sealing engagement with a well wall, said tube provided with ports communicating with said chamber for introducing fluid within said chamber for actuating said plunger over said portion, and means carried by 35 said tube adjacent said portion for engaging said plunger when actuated out of said chamber to position 40 and maintain said plunger over said portion.

5. In combination with a well tube, a packer connected in said tube and having a pair of oppositely disposed portions with one of said portions of a greater diameter than the other and constituting an expander, a housing connected to said tube adjacent said expander and circumspatially with the other portion, an expandable sleeve slidably mounted in said housing and having an inside diameter exceeded by said first mentioned diameter to effect expansion of said sleeve when the latter is actuated over said expander from said housing, and means for introducing fluid within said housing for actuating said sleeve. 45

6. A packer adapted to be connected in a well tube and formed with a pair of oppositely disposed portions with one of said portions of a greater diameter than the other and constituting an expander, a housing connected to said packer adjacent said expander and circumspatially with the other portion, an expandable sleeve slidably mounted in said housing and having an inside diameter exceeded by said first mentioned diameter for effecting expansion of said sleeve when the latter is actuated over said expander from said housing, and means for introducing fluid within said housing for actuating said sleeve. 50
